UNITED STATES PATENT OFFICE.

JOHN P. PHELPS, OF HOLYOKE, MASSACHUSETTS.

DESIGN FOR WRITING AND PRINTING PAPER.

No. 38,587.

Specification for Design.

Patented May 28, 1907.

Application filed December 31, 1906. Serial No. 350,306. Term of patent 14 years.

To all whom it may concern:

Be it known that I, JOHN P. PHELPS, a citizen of the United States of America, residing at Holyoke, in the county of Hampden and State of Massachusetts, have invented a new, original, and ornamental Design for Writing and Printing Paper, of which the following is a specification, reference being had to the accompanying drawing, forming part thereof.

The figure is a view showing my new design as applied to paper.

I claim:

The ornamental design for writing and printing paper, as shown.

JOHN P. PHELPS.
